DESIGN FOR A DRAPED PARTITION OR THE LIKE

Morris Lange, University Heights, Ohio

Application October 11, 1943, Serial No. 111,337

Term of patent 7 years

(Cl. D21—6)

To all whom it may concern:

Be it known that I, Morris Lange, a citizen of the United States, residing in the city of University Heights, county of Cuyahoga, and State of Ohio, have invented a new, original, and ornamental Design for a Draped Partition or the like, of which the following is a specification, reference being had to the accompanying drawing, forming a part thereof.

Figure 1 is a front elevation of the draped partition showing the design. The dominant feature of my design resides in the portion shown in full lines;

Figure 2 is an enlarged top plan view of the

portion of the draped partition indicated by the arrows 2—2 of the Figure 1;

Figure 3 is a fragmentary enlarged elevational view of that portion of the draped partition shown in top plan view in Figure 2 and as indicated by the arrows 2—2 of Figure 1.

Figure 4 is a vertical cross-sectional view of a part of the draped partition, taken along the line and in the direction of the arrows 4—4 of the Figure 3.

I claim:

The ornamental design for a draped partition or the like, substantially as shown and described.

MORRIS LANGE.
